EJECTOR MECHANISM FOR FIREARMS

John Crowe, St. Joseph, Mo., assignor to The
Marlin Firearms Company, New Haven, Conn.,
a corporation of Connecticut

Application May 8, 1944, Serial No. 534,556

17 Claims. (Cl. 42—48)

1

This invention relates to ejector mechanism for firearms, and more particularly to an ejector mechanism for a so-called under-and-over gun, although it will be understood that the principles of the invention are applicable to guns of other types.

As shown, the ejector mechanism is applied to a shotgun of the under-and-over type having one barrel mounted above the other. Such guns are commonly provided with a barrel section pivoted to the action frame and controlled by a lever so that the gun may be broken for ejection of the fired shells and reloaded. It is, of course, desirable that after one barrel of the gun has been fired this shell may be ejected from the barrel so that it may be reloaded without the ejection of a cartridge remaining in the other barrel, and this action should be effected regardless of which barrel has been fired. Likewise, if both barrels have been fired, both shells should be ejected when the gun is broken.

In the past the ejecting mechanism has usually been mounted in the barrel section of the gun, and in its usual form comprises a spring-actuated ejector hammer controlled by a sear or the like, the sear being released when the gun is broken. In the present invention the greater part of the ejector mechanism is mounted in the action frame, close to the action mechanism consisting of the main hammers and associated parts. By this arrangement the ejector hammers may be readily controlled by the main hammers, and I am enabled to omit entirely the employment of a sear to control the ejector hammers, the latter being both cocked and released by the movement of the main hammers to cocking position when the gun is broken. I thus avoid the placing of complicated ejector mechanism in the barrel section, and employ in this section only the connections between the ejector hammers and the ejectors themselves.

One object of the present invention is to provide improved ejector mechanism for firearms.

A further object of the invention is to provide an ejector mechanism for a firearm having an action frame and a barrel section pivoted thereto, wherein the principal working parts of the ejector mechanism are mounted in the action frame and are suitably connected to the ejectors themselves, which latter are mounted on the barrel section.

A still further object of the invention is to provide ejector mechanism for firearms of simplified construction, but which will at the same time be positive in operation, and which may be em-

2

ployed with double-barreled guns such as under-and-over guns, so that when either or both barrels of the gun have been fired the shell will be ejected from the fired barrel.

5 To these and other ends the invention consists in the novel features and combinations of parts to be hereinafter described and claimed.

In the accompanying drawings:

Fig. 1 is a view partly in section of the parts 10 of a firearm adjacent the breech thereof, showing the action mechanism and associated ejector mechanism;

Fig. 2 is a sectional view on line 2—2 of Fig. 1;

Fig. 3 is a sectional view on line 3—3 of Fig. 1;

15 Fig. 4 is a central sectional view of the lower part of the firearm on line 4—4 of Fig. 3;

Fig. 5 is a view similar to Fig. 1 but showing the main hammers of the gun in cocked positions;

20 Fig. 6 is a view similar to Fig. 5 showing the position of the parts when the gun is broken after discharge; and

Fig. 7 is a sectional view at the breech end of the barrel section, on line 7—7 of Fig. 5.

25 To illustrate a preferred embodiment of my invention I have shown a firearm comprising a barrel section 10 and an action frame 11. As shown in Fig. 7, for example, the barrel section comprises two barrels 12 and 13 mounted one above 30 the other, as is usual in an under-and-over gun.

Extending forwardly beyond the breech end of the barrel section is a portion of the action frame, which portion is of generally U-shaped form having a base 14 and upstanding spaced walls 15 and 16 which embrace the rear portion of the barrel section, as shown in Fig. 7.

The barrel section is pivoted to swing about the action frame on a transverse pivot 17, the barrel and stock portion being held in operative relation during the opening movement of the gun 40 by the usual forearm 18 which snaps in place upon the barrel. The gun is held in closed position by a locking plunger 19, the fore end of which engages in a groove 20 in a depending lug 21 on 45 the barrel section, and which plunger is controlled by a lever 22 pivoted on the action frame in the usual manner, well understood by those skilled in the art.

The action mechanism comprises upper and 50 lower main hammers 24 and 25 having firing pins 26 and 27 connected thereto and extending forwardly to the breech of the barrel section. These hammers are urged forwardly by compression springs 28 and 29 which surround rearwardly extending stems 30 and 31 having tail portions 32

and 33 with which sears 34 and 35 are adapted to cooperate. As this particular portion of the action mechanism is not a part of the invention to be protected in the present application, further description thereof is unnecessary, and its operation will be readily understood by those skilled in the art.

As shown more particularly in Figs. 3 and 4 of the drawings, the hammers are provided with laterally offset arms 36 and 37, the former extending downwardly from the upper hammer and the latter extending upwardly from the lower hammer, so that these two members lie side by side in laterally spaced relation. A cocking lever 38 is pivoted to the action frame at 39, the upper end of this lever having a crosshead 40 disposed forwardly of the arms 36 and 37 of the hammers, so that when this lever is moved in a clockwise direction about its pivot, the hammers will be moved rearwardly to cocked position.

At the central portion of the member 14 is slidably mounted a rod 41 the movement of which is limited by the screw 42 which engages in a recess 43 in the rod. The rear end of this rod engages the cocking lever 38, and its forward end engages an abutment 44 at the center of the forearm 18. It will be understood that this forearm is clamped to the barrel and swings with the barrel in the pivotal movements of the latter. As shown in Fig. 4, the rear face of the abutment 44 is cam-shaped as shown at 45, and it will be obvious that when the gun is broken the rod 41 will be moved rearwardly, and by impingement of its rear end against the cocking lever 38 will move the cocking lever from the position shown in Figs. 1 and 4 to the position shown in Fig. 6, thus moving the hammers to cocked position whenever the gun is fully opened. In other words, whenever the gun is opened both hammers are moved to cocked positions in which the tail portions 32 and 33 will be engaged and held in such positions by the sears 34 and 35, unless, of course, one or both of the hammers have not been fired and are already in cocked position.

The ejectors are slidably mounted in the barrel section, one at each side thereof, and consist of body portions 50 having the ejectors 51 at their rear ends, one of which serves to eject the shell in the lower barrel and the other in the upper barrel (Fig. 7). At their forward ends the body portions 50 are provided with laterally turned ends 52 adapted to be engaged by the upper ends of levers 53 pivoted at 54 in the side walls of the forearm, as shown more particularly in Fig. 2. It will be understood that the ejector mechanism is duplicated at each side of the gun, and hence it will be necessary to refer in this description to that on one side only.

Slidably mounted in the side wall portions 15 and 16 of the fore part of the action frame are rods 55, the forward ends of which engage the cam-shaped lower ends 56 of the levers 53. The rear ends of these rods 55 extend into the action frame and are there provided with heads 57 having therein notches 58 within which are engaged the ends 59 of ejector hammers 60 pivoted at 61 to the action frame.

Each ejector hammer is provided with a rearwardly extending arm 62 having a head portion 63, and is urged to forward position by the spring 64, which is the position shown in Fig. 1, for example. The inner face of each of the heads 63 is beveled, so that the head is thicker at its forward portion than at its rear portion, as shown at 65 in Fig. 3, the beveled portion providing a

shoulder 65^a at the top and at the inner face of the head. Each of the portions 36 and 37 of the hammers is provided with a laterally extending lug 67, which in the uncocked position of the main hammers lies forwardly of the head 63 of the ejector hammers, as shown in Fig. 1.

It may also be noted that the hammer 60 is not only arranged to move pivotally about the pivot screw 61, but, as it is clamped somewhat loosely between this screw and the adjacent portion of the action frame, the head 63 of each ejector hammer has a slight lateral movement to and from the observer, as viewed in Figs. 1, 5 and 6. It may also be noted that, as shown in Fig. 3, the springs 64 are inclined inwardly from their bases so that the head 63 of each of the ejector hammers will be urged toward an inward position. It may also be noted that this lateral movement of the ejector hammers is, of course, not sufficient to disengage the forward ends 59 thereof from the notches 58 in the rear ends of rods 55.

The movement of the ejectors may be limited by means of a screw 70 threaded into the barrel section, the head of which engages in an elongated recess 71 in the body portion 50 of the ejector.

The operation of the ejector mechanism may now be described. In Fig. 1 of the drawings it may be assumed that both barrels of the gun have been fired as both hammers stand in uncocked position, with the lugs 67 on the main hammers standing forwardly of the heads 63 of the ejector hammers. The gun may now be broken by swinging the lever 22 about its pivot in the usual manner, thus allowing the barrel section to swing upwardly, as shown in Fig. 6. During this movement the rod 41 is cammed rearwardly by the cam face 45 of the abutment 44 to move the cocking lever 38 rearwardly, and thus force the main hammers rearwardly against the tension of the springs 28 and 29 to cocked position, the full cocked position being shown in Fig. 5. During this rearward movement of the main hammers the lugs 67 engage the forward ends of the heads 63 of the ejector hammers and swing the ejector hammers in a clockwise direction about their pivots 61 and against the action of the springs 64. In Fig. 6 of the drawings I have shown the position of the parts just before the main hammers reach a fully cocked position, and it will be seen that the lug 67 on the hammer toward the observer is about to ride over the end of the head 63 of the adjacent ejector hammer. Slight additional movement of the cocking lever 38 to fully cock the main hammers will move the lug 67 rearwardly to a sufficient extent to move off the shoulder 65^a and release the head 63 and allow the ejector hammer 60 to be propelled in an anti-clockwise direction by its spring 64.

The arm 59 of the ejector hammer lying in the recess 58 propels the rod 55 forwardly to act on the lower end of the lever 53 and drive the ejector outwardly, as shown in dotted-line position in Fig. 6. The spring 64 is sufficiently strong to move the ejector hammer with a snap action and thus drive the ejector rearwardly with sufficient force to eject the exploded shell from the barrel.

It will be apparent that this ejecting action takes place only when the gun is opened, with the hammers in their forward or uncocked position in which they will lie after the gun is fired. If the gun is broken when the main hammers are in cocked position, as shown in Fig. 5, the ejector hammers will not be actuated, for, while the

cocking lever 38 will be moved rearwardly, this will have no effect on the main hammers when they are already cocked, and likewise the ejector hammers will remain stationary. In the latter event, however, the rod 55 is held in its forward position by the spring 64, and will cooperate with the lower end of the lever 53 to move the ejector rearwardly with a gradual motion, which, while not ejecting the shell, will extract it to a sufficient extent so that it may be easily withdrawn, as is desired when the gun is to be unloaded.

When the hammers are in cocked position, the lug 67 lies opposite the head 63 of the ejector hammer, as shown in Fig. 5, and against the beveled face thereof, holding this end of the ejector hammer outwardly against the action of spring 64. When the main hammer is released by the trigger, this lug moves forwardly over the beveled surface until the hammer reaches the position shown in Fig. 1, in which the lug 67 lies forwardly of the head 63 and the latter snaps inwardly under tension of the spring 64, so that it lies behind the lug 67 in position to be moved by this lug when the hammer is cocked.

It will be appreciated that, as the ejecting mechanism is duplicated at both sides of the gun, as are also the lugs 67 upon the main hammers, the cartridges will be ejected only after they have been fired. For example, if the lower barrel has been fired but not the upper one, only the lower hammer will be in position to cock and release the ejector hammer associated therewith, while the ejector hammer on the other side will remain stationary and merely move the shell in the upper barrel outwardly to a position where it can be withdrawn, and the converse will be true if the upper barrel only has been fired. Moreover, if both barrels have been fired, both shells will be ejected.

It will be apparent that I have provided a simple and efficient ejecting mechanism which avoids the employment of sears for holding the ejector hammers in cocked position, and that the ejector hammers are both cocked and released, or drawn back and released, by continued movement of the hammers in the same direction to cocked position, which occurs each time the gun is fully opened, provided, of course, the hammers are not already cocked. By simplifying the ejecting mechanism it may be conveniently mounted within the action frame of the gun closely adjacent the main hammers, so that the ejector hammers may be directly actuated thereby. The ejectors themselves are the only part of the mechanism mounted upon the barrel section, as the kicker levers 53 are, as stated, pivoted in the side walls of the forearm, while the driver rods 55 are slidably mounted in the walls of the fore part of the action frame.

While I have shown and described a preferred embodiment of my invention, it will be understood that it is not to be limited to all of the details shown, but is capable of modification and variation within the spirit of the invention and within the scope of the claims.

What I claim is:

1. A firearm comprising an action frame, a barrel section pivoted thereto, an ejector on the barrel section, a spring-actuated ejector hammer movably mounted on the action frame, means actuated by movement of the barrel section to open position about its pivot for cocking and releasing the ejector hammer, and operative connections from said hammer to said ejector.

2. A firearm comprising an action frame, a

barrel section pivoted thereto, an ejector on the barrel section, a spring-actuated ejector hammer movably mounted on the action frame, means actuated by movement of the barrel section to open position about its pivot for cocking and releasing the ejector hammer, and operative connections from said hammer to said ejector, said connections including a rod slidably mounted in a forward portion of the action frame and actuated by said hammer.

3. A firearm comprising an action frame, a barrel section pivoted thereto, an ejector on the barrel section, a spring-actuated ejector hammer movably mounted on the action frame, means actuated by movement of the barrel section to open position about its pivot for cocking and releasing the ejector hammer, operative connections from said hammer to said ejector, said connections including a rod slidably mounted in a forward portion of the action frame and actuated by said hammer.

4. A firearm comprising an action frame, a barrel section pivoted thereto, an ejector on the barrel section, a spring-actuated ejector hammer movably mounted on the action frame, means actuated by movement of the barrel section to open position about its pivot for cocking and releasing the ejector hammer, operative connections from said hammer to said ejector, a forearm on the barrel section, said connections including a rod slidably mounted in a forward portion of the action frame and actuated by said hammer, and a lever pivoted on the forearm and transmitting movement from said rod to the ejector.

5. A firearm comprising a barrel section, an action frame to which the barrel section is pivoted having forwardly spaced side wall portions embracing the rear end of the barrel section, an ejector movably mounted on the barrel section, a spring-pressed ejector hammer movably mounted on the action frame, and means operatively connecting said hammer to the ejector, said means comprising a rod movably mounted in one of said side walls.

6. A firearm comprising a barrel section, an action frame to which the barrel section is pivoted having forwardly spaced side wall portions embracing the rear end of the barrel section, an ejector movably mounted on the barrel section, a spring-pressed ejector hammer movably mounted on the action frame, means operatively connecting said hammer to the ejector, said means comprising a rod movably mounted in one of said side walls, and a member transmitting motion from the forward end of the rod to said ejector.

7. A firearm comprising a barrel section, an action frame to which the barrel section is pivoted having forwardly spaced side wall portions embracing the rear end of the barrel section, an ejector movably mounted on the barrel section, a spring-pressed ejector hammer movably mounted on the action frame, means operatively connecting said hammer to the ejector, said means comprising a rod movably mounted in one of said side walls, and means actuated by the movement of the barrel section about its pivot to both retract and release said ejector hammer.

8. A firearm comprising a barrel section, an action frame to which the barrel section is pivoted having forwardly spaced side wall portions embracing the rear end of the barrel section, an ejector movably mounted on the barrel section, a spring-pressed ejector hammer movably mount-

ed on the action frame, means operatively connecting said hammer to the ejector, said means comprising a rod movably mounted in one of said side walls, a member transmitting motion from the forward end of the rod to said ejector, and a forearm connected to the barrel section, and said member comprising a lever pivoted to said forearm, the ends of said lever engaging said rod and ejector respectively.

9. A firearm comprising a barrel section, an action frame to which the barrel section is pivoted having forwardly spaced side wall portions embracing the rear end of the barrel section, an ejector movably mounted on the barrel section, a spring-pressed ejector hammer movably mounted on the action frame, means operatively connecting said hammer to the ejector, said means comprising a rod movably mounted in one of said side walls, and a cocking lever actuated by the swinging of the barrel section about its pivot to effect both cocking and release of said ejector hammer.

10. A firearm comprising an action frame, a barrel section pivoted thereto to permit breaking of the gun, an ejector on the barrel section, a spring-actuated ejector hammer movably mounted on the action frame, operative connections from said hammer to said ejector, a main hammer movably mounted in the action frame, means to cock said main hammer, and means to effect cocking and release of said ejector hammer when said main hammer is cocked.

11. A firearm comprising an action frame, a barrel section pivoted thereto to permit breaking of the gun, an ejector on the barrel section, a spring-actuated ejector hammer movably mounted on the action frame, operative connections from said hammer to said ejector, a main hammer movably mounted in the action frame, means to effect cocking and release of said ejector hammer when said main hammer is cocked, and means to cock said main hammer by a pivotal movement of the barrel section relatively to the action frame.

12. A firearm comprising an action frame, a barrel section pivoted thereto to permit breaking of the gun, an ejector on the barrel section, a spring-actuated ejector hammer movably mounted on the action frame, operative connections from said hammer to said ejector, a main hammer movably mounted in the action frame, means for cocking said main hammer, and means to effect operative movement of said ejector hammer when said main hammer is cocked, said means permitting said main hammer, when released, to move forwardly without operative effect upon said ejector hammer.

13. A firearm comprising a barrel section, an action frame to which the barrel section is pivoted having forwardly spaced side wall portions embracing the rear end of the barrel section, an ejector movably mounted on the barrel section, a spring-pressed ejector hammer movably mounted on the action frame, means operatively connecting said hammer to said ejector, said means comprising a rod movably mounted in one of said side walls, a member transmitting motion from the forward end of the rod to said ejector, a main hammer movably mounted in the action frame, means for cocking said main hammer, and means to effect both cocking and release of

8
said ejector hammer when said main hammer is cocked.

14. A firearm comprising a barrel section, an action frame to which the barrel section is pivoted having forwardly spaced side wall portions embracing the rear end of the barrel section, an ejector movably mounted on the barrel section, a spring-pressed ejector hammer movably mounted on the action frame, means operatively connecting said hammer to said ejector, said means comprising a rod movably mounted in one of said side walls, a member transmitting motion from the forward end of the rod to said ejector, a main hammer movably mounted in the action frame, means to effect both cocking and release of said ejector hammer when said main hammer is cocked, and means to cock said main hammer by pivotal movement of the barrel section.

15. A firearm comprising a barrel section, an action frame to which the barrel section is pivoted having forwardly spaced side wall portions embracing the rear end of the barrel section, an ejector movably mounted on the barrel section, a spring-pressed ejector hammer movably mounted on the action frame, means operatively connecting said hammer to said ejector, said means comprising a rod movably mounted in one of said side walls, a member transmitting motion from the forward end of the rod to said ejector, a main hammer on said action frame, means for cocking said main hammer, and a member on said main hammer to engage and cock, and then release, said ejector hammer when the main hammer is moved to cocked position.

16. A firearm comprising a barrel section, an action frame to which the barrel section is pivoted having forwardly spaced side wall portions embracing the rear end of the barrel section, an ejector movably mounted on the barrel section, a spring-pressed ejector hammer movably mounted on the action frame, means operatively connecting said hammer to said ejector, said means comprising a rod movably mounted in one of said side walls, a member transmitting motion from the forward end of the rod to said ejector, a main hammer on said action frame, means for cocking said main hammer, and a member on said main hammer to engage and cock, and then release, said ejector hammer when the main hammer is moved to cocked position, said main hammer when released passing by said ejector hammer without effecting operative movement thereof.

17. A firearm comprising a barrel section, an action frame to which the barrel section is pivoted having forwardly spaced side wall portions embracing the rear end of the barrel section, an ejector movably mounted on the barrel section, a spring-pressed ejector hammer movably mounted on the action frame, means operatively connecting said hammer to said ejector, said means comprising a rod movably mounted in one of said side walls, a member transmitting motion from the forward end of the rod to said ejector, and a main hammer on said action frame, means for cocking said main hammer, said main hammer having a laterally extending part engaging said ejector hammer to cock the latter when the main hammer is cocked, but passing by said ejector hammer when the main hammer is released.

JOHN CROWE.
